UNITED STATES PATENT OFFICE.

WILLIAM H. S. MOORE, OF CLEVELAND, OHIO.

PLIERS.

Application filed January 15, 1921. Serial No. 437,382.

To all whom it may concern:

Be it known that I, WILLIAM H. S. MOORE, a citizen of the United States, residing at Cleveland, in the county of Cuyahoga and State of Ohio, have invented a certain new and useful Improvement in Pliers, of which the following is a full, clear, and exact description.

The present invention relates to pliers 10 and more particularly so called carpenters' pliers which are used to extract nails from wood or other substances.

Reference should be had to the accompanying drawings in which Fig. 1 is a side 15 elevation of the pliers; Fig. 2 is an elevation of a portion of the opposite side of the pliers to that shown in Fig. 1; Fig. 3 is a top plan view and Fig. 4 is a front elevation.

20 Carpenters or other persons making or working with wooden articles or articles of analogous material are frequently under the necessity of extracting nails, particularly short wire nails or brads which are too 25 small to be operated upon by the usual claws of a hammer and for this purpose carpenters' pliers are used which are provided with jaws that may be manipulated to bite the nail and further manipulated to extract the 30 nail.

The pliers which form the subject matter of the present invention are for a similar purpose but are so formed as to permit access of the head of the pliers to positions 35 and the use of the pliers under conditions where the usual forms of pliers cannot get close enough to the nail to grip it, as for instance where the nail to be removed is close to an upstanding board or in the corner.

40 In the present instance the pliers are formed by two pivoted members, these members having hand gripping portions 1 and 2 and provided with cheek portions 3 and 4 which are in engagement and are secured in engagement with each other by means of a pin 5. Each of the gripping portions 2 and 3 are provided with a head, the head for the member 4 being indicated at 6 and 45 the head for the member 1 being indicated at 7. The head members 6 and 7 are in alignment and the parts are so assembled that when the grip portions 1 and 2 are brought together, the head portions likewise 50 move toward each other and into engagement.

The head member 6 has a straight top portion 6^a and a short right angle portion 6^b which terminates in jaws such as indicated at 6^c, there being two jaws 6^c which are separated by a space. The head member 7 has a long arm 7^a which terminates in two jaws 7^b, these jaws cooperating with the jaws 6^c. The arm 7^a is rounded at the portion indicated at 7^c as clearly indicated in the drawing.

60 The plane of the top surface 6^a of the jaw 6 is slightly above the grip member 1 so that in manipulating the pliers to get hold of a nail which is near an upstanding board, 70 or in other words near a corner, the surface 6^a may be moved up against the board and still leave room enough for the fingers to get behind the gripping member 1.

75 When the jaws of the pliers are closed upon a nail, the pliers are used as a lever, the arm 7^a with its curved portion 7^c are rocked upon the surface at which the nail is positioned, thus effecting a lever movement which will make the removal of the 80 nail much easier than a direct pull. The double gripping ridges on each jaw, afford two points of contact with a nail which makes the biting action more certain and lessens the danger of cutting the nail in 85 two. The jaw members 6^c and 7^b are provided with extensions 6^d and 7^d. These extensions permit the nail to be gripped where the nail lies too flush to the board in which it is driven to be grasped by the jaws 6, or 90 where a nail has been driven flush with the board and it is desired to extract it, the wood may be removed in the proximity of the head of the nail and start it and extract the nail.

95 The particular advantage of the pliers constructed as herein described lies in the fact that by having the head 6 with a flat plane side and having the jaw of the head 6 close to the head, the pliers may be inserted into corners and used to grip nails near upstanding boards where the same could not be done with usual pliers.

100 Additionally, by having the jaw 7 with its long side 7^a, gives a much more effective 105 leverage on the nail than can be obtained with pliers of usual construction.

Having described my invention, I claim

110 1. Pliers comprising a pair of crossed pivoted handle portions and oppositely disposed heads, one of said heads being straight with a short jaw member, the other head

being curved and having a long jaw member, the said jaw members terminating in directly opposed gripping portions.

2. Pliers comprising a pair of crossed pivoted handle portions and oppositely disposed heads, one of said heads being straight with a short jaw member, the other head being curved and having a long jaw member, each of said jaw members being provided at 10 its end portion with a plurality of parallel gripping portions, the gripping portions on each jaw being spaced apart and the gripping portions of one jaw being directly opposed to those of the other jaw.
3. Pliers comprising a pair of crossed pivoted handle portions and oppositely disposed heads, one of said heads being straight with a short jaw member, the other head being curved and having a long jaw member, 20 each of said jaw members terminating in gripping portions, the said gripping portions extending laterally on both sides of each of the jaws.

4. Pliers comprising a pair of crossed pivoted handle portions and oppositely dis-

posed heads, one of said heads being straight with a short jaw member, the other head being curved and having a long jaw member, each of said jaw members terminating in gripping portions, the said gripping portions extending laterally on both sides of each of the jaws, each of said gripping portions being formed with parallel ridges which ridges are spaced apart.

5. Pliers comprising a pair of crossed pivoted handle portions and oppositely disposed heads, one of said heads having a straight outer edge surface, the plane of said surface extended, being outside of the handle portion which is associated with the other head of the pliers when the pliers are in gripping position, the said head being provided with an inwardly extending jaw member, the other head being curved and having a long jaw member, said jaw members having cooperating directly opposed gripping portions.

In testimony whereof, I hereunto affix my signature.

WILLIAM H. S. MOORE.
